UNITED STATES PATENT OFFICE.

BENJAMIN D. BERRY, OF CHESTER, PENNSYLVANIA, ASSIGNOR OF ONE-HALF TO WILLIAM H. BERRY, OF CHESTER, PENNSYLVANIA.

SASH-HOLDER.

SPECIFICATION forming part of Letters Patent No. 703,889, dated July 1, 1902.

Application filed June 4, 1901. Serial No. 63,105. (No model.)

To all whom it may concern:

Be it known that I, BENJAMIN D. BERRY, a citizen of the United States, residing at Chester, in the county of Delaware and State of Pennsylvania, have invented a new and useful Improvement in Sash-Holders, of which the following is a full, clear, and exact description, reference being had to the accompanying drawings, and to the numerals and letters of reference marked thereon.

The object of my invention is to adapt window-sashes, screens, or similar sliding devices to be freely held within their guides, so that they may be readily moved up and down therein and also conveniently tightened, and thus prevented from rattling, and, furthermore, held at any adjusted height and locked in the closed position.

It is well known that the difficulties intended to be overcome by this invention are common in the use of window-sashes, particularly those made of the softer and cheaper woods, of which the greater majority are manufactured, they being peculiarly exposed to the danger of swelling during damp weather, so that if the sash is not given freedom within its guides it will become jammed or difficult of manipulation. At the same time it has been found that where in such cases sufficient freedom has been provided within the guides to secure the sash against the danger of becoming jammed by swelling it has been necessary in order to prevent the rattling referred to to wedge the sash within the guides or otherwise secure it, which is a matter of considerable inconvenience and labor, involving the use of contrivances unsightly to the eye and injurious to the sash.

In the accompanying drawings, Figure 1 is a part elevation of a portion of a window sash and frame to which my invention is applied. Fig. 2 is a horizontal section on the line 1 1 of Fig. 1. Fig. 3 is a view similar to Fig. 2, except that the parts are shown in different positions. Fig. 4 is a section on the line 2 2 of Fig. 1. Fig. 5 is an elevation, upon reduced scale, illustrating the general arrangement of the parts of my invention with respect to a window-frame and its sashes. Fig. 6 is an under side view of the operating-plate. Fig. 7 is a view of a detail here-

inafter described. Fig. 8 is a vertical section through a window-frame and its contained sash on the line 8 8 of Fig. 5. Figs. 9 and 10 are respectively a vertical and a horizontal section on the correspondingly-numbered lines of a car-window embodying my invention in a modified form. Fig. 11 is a vertical section of a car-window, illustrating a further modification.

Similar characters of reference indicate similar parts in the respective figures.

1 1 may represent generally the window-frame; 2 2, parts of the upper and 3 3 parts of the lower sash frame. As seen particularly in Fig. 4, the lower horizontal bar of the upper-sash frame is provided with a ledge *a*, while the upper bar of the lower-sash frame 3 is furnished with an overhanging projection *a'*, the two bars when the sashes are closed occupying the position shown in said figure. Secured to the top of the lower-sash frame 3 is a plate 4, having a central projection 4^a, provided with an elongated slot 4^c, the plate serving as a support to two slidably 70 interiorly-screw-threaded thimbles 5, in each of which is screwed the end of a rod 6, employed for a purpose hereinafter described. Each of the thimbles 5 is furnished with a pin 5^a, the two pins fitting each in a separate cam-groove 5^b of an operating-plate 7, which is provided with a handle having a finger-button 7^a. The cam-plate 7 is furnished with a tubular projection or sleeve 7^d, which passes through the elongated slot 4^c, and 85 through the sleeve 7^d is passed a threaded pin 7^e, having a nut 7^f, and by means of the head and nut of said pin 7^e the cam-plate is prevented from detachment from the plate 4. At the opposite end or side of the cam-plate 90 7 is a cam or incline 7^b, which, as hereinafter more particularly described, operates in connection with the catch 8, attached to the top of the lower bar of the upper-sash frame 2, as represented more particularly in Fig. 4. 95

As seen especially in Figs. 2 and 3, the vertical strip, usually known as the "parting-strip," 9, located between the upper and lower sash frames and acting as a part of the guide for said frames, is mounted upon vertical 100 pivots 9^a 9^b, having bearings in the upper and lower horizontal portions of the window-

frame, as shown in Fig. 5. Each of these parting, or, as I will term them, "division," strips is, as seen in Figs. 1 and 3, rabbeted, as at 10, to receive the member 11 of a casting 12, one of said castings being secured to an end of each of the rods 6, each rod being turned up or hooked, as represented at 6^a, passed through a hole in the eye 13 of its casting 12, and riveted over, as shown at 14. 5
10 Each of the castings 12 rests upon a plate 15, screwed or otherwise secured to the top of the upper horizontal member of the lower-sash frame, each plate being provided with a boss 15^a, seated in an elongated slot 16 of the 15 plate. The construction is such that each plate 12 may be rocked upon its boss 15^a, as will be clearly understood from a comparison of the position of the plates shown, respectively, in Figs. 2 and 3. It will be seen by 20 reference to said figures that each division-strip 9 is capable of being rocked from its normal to the oblique position, (seen in Fig. 2,) each of said strips 9 occupying a reverse position with respect to each other, as shown in 25 Fig. 2. This rocking of the strips 9, as will be readily understood, is effected by means of the partial rotation of the cam-plate 7, whose cam-grooves 5^c, acting upon the pins 5^a of the thimbles 5, will effect the longitudinal movement 30 of the rods 6, connected to the plates 12, having engagement with said strips 9.

The division-strips 9 do not stand in a true vertical position, but have a slight outward inclination at the top, as clearly shown in 35 Fig. 8, the object of which arrangement is to cause the strips when turned on their pivots to first impinge or bear at their extreme ends upon the upper and lower sashes and allow the twist or spring in the strips to be spent 40 before the final contact with the upper and lower sashes along their entire length takes place, thus insuring a firm pressure of the strips against the whole height of both sashes.

Having thus generally described the construction of the principal parts of my invention, other features thereof will be explained in the statement of the operation of the invention which follows.

The window-sash having been fitted up 50 with the parts above described, and considerable clearance having been provided between the faces of the upper and lower sash frames, the window-guides 15^c, and the division-strips 9, so that under normal conditions the frames may be moved with the greatest ease without danger of sticking or jamming from any cause, and it is desired to raise or lower a sash, this is done in the ordinary way, all the parts being free, as seen in 55 Fig. 3. It will be seen that the plates 12, which are secured to the lower sash, are free to move with it upon the division-strips 9. The lower sash (or the upper sash, as may be) having been raised or lowered, and it is 60 desired now to secure the sash-frames from lateral movement, thus preventing rattling, the cam-plate 7 is partially rotated, and by

means of the conjoint action of the cam-grooves 5^c and pins 5^a the rods 6 will rock the plates 12 and the engaged division-strips 9, 70 throwing opposite corners or edges of each of said strips against the adjacent faces of the upper and lower sash frames, causing the outer faces of said frames to be tightly pushed and jammed against the guides 15^c, while the 75 strips 9 themselves will bind the adjacent faces of said sash-frames, all as clearly shown in Fig. 2. It will be seen that not only do the division-strips 9 serve as means for tightening the sash-frames by jamming them 80 against the guides 15^c in the manner stated, but also that they serve to make a perfectly tight joint, excluding drafts, dust, &c., from entrance between the sash-frames.

Supposing the window to be closed, the upper and lower sash frames being then in the position shown in Fig. 4, and it is desired to make tight closure between the upper and lower sash frames, as seen in Fig. 4, this is done by bringing the cam or incline 7^b of the cam-plate 7 under the catch 8, secured to the upper sash, this action being coincident with that which effects the closure at the sides of the sash along their entire height by means of the change of position or rocking 95 of the division-strips 9.

The function of the slot 4^c in the projection 4^a of the plate 4 (see Fig. 1) is to allow the independent automatic operation of one of the division-strips in the event that the other 100 should be prevented from moving through as large an arc by a greater swelling of the parts on one side of the window, the construction provided making one strip the fulcrum for the movement of the other. This would not 105 be the case were the sleeve or tubular projection 4^d, resting within the slot, fitted in a concentric opening.

Figs. 9, 10, and 11 illustrate my invention as applied to windows having a single sash, 110 particularly car-windows, in which curtains or slatted blinds are used to keep out the direct rays of the sun. In the form represented in Figs. 9 and 10, in which a curtain is used, the division-strips 9 are applied between the sash and the outside sash-guide 15^c, 115 whereas in such windows as have slatted blinds the division-strips are placed between the sash-frame and the blind. The operating-plate 7 in this form of the invention is 120 placed below the sill and within the framing of the car, the finger-button 7^a on the operating-plate extending into the car in convenient position to be manipulated. The rods 6 extend laterally from the operating-plate 7, 125 each rod being connected at its outer end to an arm 12^a, secured to the lower pivot-pin 9^a of a division-strip 9.

It is obvious that my improvement is capable of various changes and modifications 130 which will readily suggest themselves to the skilled mechanic without the exercise of invention, and such minor or unimportant changes, not departing substantially from

what is herein described, I consider as fully within my claims.

Having thus described my invention, I claim—

- 5 1. In a sash-holder, the combination of upper and lower sash frames, guides for the same, pivoted division-strips between the sash-frames adapted to engage by their edges with the side bars of said sash-frames and 50
 10 press them against the guides, and means for rocking said division-strips, substantially as set forth.
2. In a sash-holder, the combination of upper and lower sash frames, guides therefor, a 15 vertically-pivoted inclined division-strip on each side of and between the sash-frames, a plate pivoted at each end of the horizontal meeting-bar of one of the sash-frames, said plate loosely engaging the adjacent division- 20 strip and adapted to slide thereon when the sash-frame is raised or lowered, and means for rocking the plates and division-strips, substantially as set forth.
3. In a sash-holder, the combination of upper and lower sash frames, guides for the same, pivoted division-strips, and means for rocking said division-strips, substantially as 25 set forth.
4. In a sash-holder, the combination of upper and lower sash frames, their guides, a vertically-pivoted inclined division-strip on each side of and between the sash-frames, a plate pivoted at each end of the horizontal meeting-bar of one of the sash-frames, said plate 30 loosely engaging the adjacent division-strip and adapted to slide thereon when the sash-frame is raised or lowered, a rotatable plate pivoted to the horizontal bar and having cam-grooves formed thereon, and rods connecting 35 said pivoted plates to the cam-plate, substantially as set forth.
5. In a sash-holder, the combination of upper and lower sash frames, their guides, vertically-pivoted division-strips adapted to 40 force by their edges the side bars of the sash- 45
- frames into closer contact with the guides, a catch on the lower horizontal bar of the upper sash, a rotatable plate pivoted to the upper horizontal bar of the lower sash, said rotatable plate being provided with cam-grooves 50 and an inclined flange by means of which the division-strips are forced against the guides and the sashes locked together by the one operation, substantially as set forth.
6. In a sash-holder, the combination of upper and lower sash frames, their guides, pivoted division-strips adapted to engage by their edges with the side bars of the sash-frames and press them against the guides, a 55 plate loosely engaging each division-strip and 60 adjusted to slide thereon, and means for rocking the plates and the division-strips, substantially as set forth.
7. In a sash-holder, the combination of upper and lower sash frames, their guides, pivoted division-strips between the sash-frames and having a slight inclination toward the upper sash, and means for rocking said division-strips whereby they are caused to impinge or bear on the sash-frames first at the 65 extreme ends and finally for their whole length, substantially as set forth.
8. In a sash-holder, the combination of upper and lower sash frames, their guides, pivoted division-strips, a cam-plate pivoted at 70 the center of the upper horizontal bar of the lower-sash frame, a plate pivotally secured at each end of said bar, each engaging a division-strip and adapted to slide thereon with the lower-sash frame, and connections between the cam-plate and said pivoted plates 75 whereby, upon the rotation of the cam-plate, said division-strips may be turned upon their pivots, substantially as set forth.

In testimony whereof I hereunto set my 80 hand and seal.

BENJAMIN D. BERRY. [L. S.]
